FLYING SAUCER TOY

Leonard Gray, Sharon, Mass., and Carl Cederholm, Providence, R.I., assignors to Hasbro Industries, Inc., Pawtucket, R.I., a corporation of Rhode Island

Filed Aug. 18, 1969, Ser. No. 18,742

Term of patent 14 years

Int. Cl. D21—02

U.S. Cl. D34—15

FIG. 1

FIG. 2

FIG. 3

FIG. 1 is a top plan view of a flying saucer toy showing our new design;

FIG. 2 is a bottom plan view thereof; and

FIG. 3 is a side elevational view thereof.

We claim:

The ornamental design for a flying saucer toy, substantially as shown.
